(57) **CLAIM**

The ornamental design for a display screen with graphical user interface, as shown and described.

DESCRIPTION

FIG. 1 is a first embodiment of a front view of a display screen with graphical user interface showing the new design. FIG. 2 is a second embodiment of a front view of a display screen with graphical user interface showing the new design. FIG. 3 is a third embodiment of a front view of a display screen with graphical user interface showing the new design. FIG. 4 is a fourth embodiment of a front view of a display screen with graphical user interface showing the new design; and,

FIG. 5 is a fifth embodiment of a front view of a display screen with graphical user interface showing the new design. The broken lines of uneven length in FIGS. 1-5 show the display screen and form no part of the claimed design. The portion of the graphical user interface shown in broken lines of even length illustrate portions of the graphical user interface that form no part of the claimed design. The solid black dots within the grids in all of the figures are not part of the claimed design.
